Barrington, Ill.

Filed Feb. 18, 1960, Ser. No. 59,439

Term of patent 14 years

(Cl. D65—1)

The figure is a front perspective view of a pump, embodying my new design.

The dominant features of my design reside in the portions shown in full lines.

The rear and the side not shown are substantially plain and unornamented.

I claim:

The ornamental design for a pump, substantially as shown and described.
